UNITED STATES PATENT OFFICE.

JOHN LALLY, OF BOSTON, MASSACHUSETTS.

BUILDING COLUMN.

Application filed September 13, 1921. Serial No. 500,384.

To all whom it may concern:

Be it known that I, JOHN LALLY, a citizen of the United States, residing at Boston, Suffolk County, Massachusetts, have 5 invented a new and useful Improvement in Building Columns, of which the following is a specification.

My invention relates to building columns of the tubular casing, concrete filled type 10 with a top or crown built up of cut pieces interlocked with the casing and it is my object to provide such columns with improved means for attaching floor beams and the like and with means for connecting superimposed columns which means will be as small and light as possible and at the same time have great weight bearing capacity.

In the drawings Fig. 1 is a side view, partly in section of a column top embodying my invention; Fig. 2 a sectional view 20 of the structure of Fig. 1 on the line 2—2 thereof; Fig. 3 a like view of the structure of Fig. 1 on the line 3—3 thereof; Fig. 4 a side view of a somewhat simplified form 25 of column and beam connection; and Fig. 5 a view partly in section of a column having a beam connection and bracket on one side thereof.

The column comprises the outer casing 1 of steel tubing or cast iron and is slotted 30 at 2—2, the points where the beam connections are to be made.

In the form shown in Figs. 1, 2 and 3 the slots are not diametrically opposed. A tie plate 3 is bent at 4 so that its end portions 35 are parallel but off-set and is provided with notches 5—5. The plate 3 is pushed through the slots 2—2 with the notches 5—5 engaging the upper ends of the slots and wedges 40 6—6 are driven into the lower ends of the slots to force the tie plate up into firm contact with the casing, the notches preventing lateral movement. The wedges and plates, or either, may be welded to the casing 45 if desired.

Under each upper slot and alined therewith is a second slot 7—7. Brackets 8—8 are hooked therein. These brackets have a shelf 9, web 10 and hook-like projections 11 50 and 12 which are hooked inside the casing. A wedge 13 is inserted to fill the end of the slot. This bracket and wedge may also be welded to the casing if desired. The column is then inverted and filled with plastic 55 material such as concrete which not only

strengthens it and aids in fire-proofing it but also aids in uniting the parts into an integral structure.

The floor beams 14—14 are laid on the brackets 8—8 and secured to the tie plate 60 3 by rivets 15—15. Bolts may be used if desired. The tops of these floor beams are generally flush with the top of the column.

If another column 15' is to be superimposed a sandwich plate 16, provided with a 65 central opening, is laid on or secured to the top of the lower column and a dowel pin 17 passes through the plate aperture and engages the plastic filling in the upper and lower columns. The top plate 16 may be 70 the same size as the columns or larger, and if square, as shown in Fig. 3, will form substantially a continuation of the upper flanges of the floor beams.

It will be noted that the bend 4 in the tie 75 plate 3 permits the beams 14—14 to substantially aline the middle of the column so that the load is evenly borne.

If a third floor beam or a single beam is to be attached the upper and lower alined 80 slots 18 and 19 are cut at the proper places and a bracket 20 and tie plate 21 are inserted in the slots and secured as before described. The tie plate 21 does not, in this case, pass entirely through the casing. 85

In the form shown in Fig. 4 the tie plate 22 is placed in slots in the lower part of the upper column 23 and the sandwich plate 24 is placed on the top of the lower column 25. By this construction the floor beams rest on 90 brackets on the lower column and are secured to a tie plate in the upper column thus uniting the two columns. The dowel pin 26 may be used or not as desired.

In Fig. 5 I have also shown how a sandwich plate the size of the lower column may have a column of lesser diameter superimposed upon it.

I claim:

1. A building column comprising a casing 100 provided with a slot, a notched tie plate entering said slot and extending partly within and partly without the casing and adapted to engage the side of a floor beam, the notch in the tie plate engaging the slot end, 105 a bracket secured to the casing below the tie plate adapted to carry a floor beam.

2. A building column comprising a casing 110 provided with upper and lower slots, a notched tie plate entering the upper slot

with the notch engaging the slot end, a bracket in the lower slot, a hook on said bracket within the casing and plastic material within the casing.

5 3. A building column comprising a casing provided with a slot, a notched tie plate entering the slot with the notch engaging the slot end, a wedge in said slot opposed to the notch whereby the notch and slot are forced together, and a bracket secured to the casing below the tie plate.

4. A building column comprising a casing provided with opposed, aligned slots, a notched tie plate extending through the slots and casing and beyond the latter with the notches engaging the casing, wedges in the ends of the slots opposed to the notches and forcing the notches into engagement with the slot ends, brackets secured to the casing below the tie plates and a filling of plastic material within the column.

5 5. A building column comprising a casing provided with upper and lower opposed, aligned slots, a notched tie plate extending through the upper slots and casing and extending beyond the latter with the notches engaging the slot ends, brackets, each having inner hook-like parts engaging the lower

slots below the tie plate and a filling of plastic material within the casing. 30

6. A building column comprising a casing provided with slots slightly staggered with respect to one another but substantially opposed, a tie plate having a bend therein with its ends substantially parallel extending through the slots and casing and beyond the latter with the bend inside the casing, brackets secured to the casing below the tie plate and a filling of plastic material within the casing. 35

7. Building construction comprising a column casing provided with opposed slots, a notched tie plate in the slots and extending through and beyond the casing with the notches engaging the slot ends, a bracket and plate below the column and a second column under the first carrying the bracket and plate, said bracket and tie plate being adapted to be secured to a floor beam whereby the floor beam is secured to both the 45 upper and lower columns securing the two together. 50

In testimony whereof I have hereunto subscribed my name.

JOHN LALLY.
